(74) Attorney, Agent, or Firm—Pillsbury Winthrop Shaw Pittman LLP

(57) **CLAIM**

The ornamental design for a demolition tool, as shown and described.

DESCRIPTION

FIG. 1 is a perspective illustration, from the front and left side, of a demolition tool according to our design;

FIG. 2 is a side elevational view thereof from the left side;

FIG. 3 is a top plan view thereof;

FIG. 4 is a front elevational view thereof;

FIG. 5 is a side elevational view thereof from the right side;

FIG. 6 is a bottom plan view thereof; and,

FIG. 7 is a back elevational view thereof.
